UNITED STATES PATENT OFFICE.

WILLIAM C. STEWART, OF LYNN, MASSACHUSETTS, ASSIGNOR TO MANUFACTURERS MACHINE COMPANY, OF MONTCLAIR, NEW JERSEY, A CORPORATION OF NEW JERSEY.

INSOLE-SLASHING MACHINE.

No. 871,967.

Specification of Letters Patent.

Patented Nov. 26, 1907.

Application filed May 10, 1906. Serial No. 316,102.

To all whom it may concern:

Be it known that I, WILLIAM C. STEWART, a subject of the King of Great Britain, and a resident of Lynn, county of Essex, State of Massachusetts, have invented an Improvement in Insole-Slapping Machines, of which the following description, in connection with the accompanying drawings, is a specification, like letters on the drawings representing like parts.

This invention has for its object to provide a machine for slapping insoles, employed in the manufacture of boots and shoes, for the purpose of rendering such soles and the shoes of which they constitute a part more flexible than would otherwise be the case.

While my invention may be employed in slapping any kind of insole, it has peculiar advantages in connection with what are known as welt insoles employed in the manufacture of welted shoes.

The welt insole is provided around its margin or periphery with a channel and lip to which the upper and welt are subsequently stitched and, obviously, the slashes employed for flexing the sole must not extend through or beyond this channel, for the latter must remain intact for retaining and holding the stitches which secure the upper and welt in position. Because of this marginal channel lip it is impossible to run the sole transversely between slapping rollers or cutters as is done with "McKay" soles; consequently it has been customary to employ gangs of slapping knives depending from a common head with means for depressing this head upon the sole to slit it transversely within the lip, the knives being so shaped and adjusted as to embrace an area well within the area bounded by the lip. An objection to machines of this type is that the knife or knives must be adjusted for every change in width of sole if the slashes are to be carried in every case to a given distance within and from the lips at the two sides of the sole. Another objection is that rights and lefts require differently adjusted knives or blades, so that in practice such frequent adjustments and exchanges of knives are required in this type of machine as to render it in a large measure impracticable for commercial use in large factories.

My invention aims among other things to

provide a machine through which the welt insoles, in fact any kind of an insole, may be fed as between rollers, and suitable means is provided for causing the slashes, which preferably are made successively, to vary in length according to the separation of the lips in the lines of the respective slashes or according to the varying contours of the soles, irrespective of size or width, and whether they be rights or lefts.

My invention will be best understood from a description of one embodiment thereof, illustrated in the accompanying drawings.

In the said drawings, — Figure 1 is a face view of a machine illustrating my invention; Fig. 2 is a righthand elevation of the machine illustrated in Fig. 1; Fig. 3 is a lefthand elevation of said machine with the driving pulley, partially broken away to show the driving clutch in section; Fig. 4, a vertical, sectional detail on the dotted line 4—4, Fig. 1; Fig. 5, a diagrammatic view illustrating one form of means for forming a slashed area having the contour of the lip or sole; Fig. 6, a sectional detail on the dotted line 6—6, Fig. 1; Fig. 7, a detail partially in section on the dotted line 7—7, Fig. 1, showing the means for endwise reciprocating the slapping knife to produce in the machine shown transverse slashes differing in length; Fig. 8, a sectional detail on the dotted line 8—8, Fig. 1; Fig. 9, a sectional detail on the dotted line 9—9, Fig. 3, to be referred to, and Fig. 10, a diagram illustrating the manner of slapping a sole by the embodiment of my invention here illustrated.

In the particular embodiment of my invention selected for illustration herein and shown in the drawings, referring first to Figs. 1—3, inclusive; the frame 1 is shown as comprising a bed piece, with side members having upwardly inclined or oblique front faces, as indicated. In the upper ends of these side members is journaled the main drive shaft 2, provided at one end with a driving pulley, 3, loose thereon, and adapted to be connected at will with and to rotate said shaft through the medium of any suitable or desired clutch mechanism.

In the present embodiment of my invention, see Fig. 3, I have shown a friction clutch, 4, of the well-known "roller" type, the same comprising a hub fast on the shaft

and provided with inclined faces, 5, coöperating with which are rollers, 6, in a cage, 7, all within a housing, 8, fast to the pulley. A spring, 9, connects the housing with the 5 roller cage and tends to draw the latter normally to engage the rollers with the inclines, 5, on the collar, the cage being provided with a radially extended ear, 10, by which to control the engagement and disengagement of the rollers with said inclines in a 10 manner to be hereinafter described. Fast on said shaft, 2, between its bearings, is an eccentric, 11, see Fig. 1, embraced by an eccentric strap, 12, adjustably connected 15 by a rod, 13, with a slide, 14, mounted in suitable guides or ways, 15, on the inclined front faces of the side frame members, 1, whereby rotation of said shaft will cause reciprocation of said slide.

20 It will be noticed in Fig. 1 that instead of connecting the eccentric rod, 13, with its slide by a usual wrist pin construction, said rod is connected universally, as by a ball and socket joint, with said slide whereby the 25 eccentric rod may be screwed into its strap, 12, and adjusted to any degree of nicety by partial rotation, which would be impossible if a wrist pin were employed, because the latter would always require a half turn or a 30 multiple thereof for adjusting.

The slide, 14, at its lower edge is provided top and bottom, see Fig. 3, with two flanged guide plates, 16, between which is mounted to slide transversely a knife carrier, 17. 35 This knife carrier, see Fig. 1, presents two downwardly extended arms, which embrace between them the knife, 18. The edges of this knife are preferably beveled at its opposite corners to enter correspondingly 40 shaped grooves in the carrier arms, the latter being provided with a draw screw, 19, by which they may be drawn to clamp them tightly to the edges of said knife to hold the latter in desired adjusted position. To facilitate nice adjustment of the knife, the latter is supported at its upper end by a set screw, 20, which, when the knife is released by slackening the screw, 19, may be turned more or less to force said knife forward, or to 50 permit it to be pushed inward, as may be desired, after which it is clamped by the screw, 19. Obviously, reciprocation of the slide, 14, will cause corresponding reciprocation of the knife, 18, imparting to the latter what may be likened to a rapid chopping action.

The knife blade is of one invariable width and will of course always make a cut of one invariable length, which, for the best results, should be equal to the shortest cut to be made in any insole to be operated upon. As the cut progresses from the toe end of the sole towards the widest or ball part thereof the cuts or slashes obviously should progress

in length to keep pace with the widening sole, 65 and to accomplish this with a knife of fixed width, as shown, my invention contemplates making two cuts with the knife for each step feed of the sole, the first cut being made next one edge of the sole and extending inward 70 more or less across the sole and then as the knife is withdrawn it is moved endwise, or across the sole, into a corresponding position relative to the opposite edge of the sole and given a second cutting movement to cut the 75 sole in line with and in extension of the first cut, the two cuts together forming one continuous slash across the sole from edge to edge thereof or from margin to margin of the desired slashed area of the sole. The two 80 successive cuts will of course overlap more or less at the middle of the sole according to the width of sole; thus at the narrower portions of the sole the two cuts will be almost superimposed one upon the other, while at the 85 widest portions of the widest soles the two cuts will be made practically end to end with little or no overlap. This is illustrated in Fig. 10, where the first of the pairs of successive cuts necessary to produce a slash 90 across the sole are indicated by the double parallel lines marked "a" and the second of the pairs of cuts, in extension of the first, are shown by the single lines marked "b". It will be seen that these cuts overlap to a 95 greater extent in the vicinities of the narrow portions of the sole than at the wider portions thereof. It is evident, therefore, that for every step feed there must be two downward or chopping strokes of the cutter and 100 that between each pair of downward strokes of the cutter the latter is moved endwise across the sole from one to the opposite edge thereof, this endwise movement being obtained by sliding the knife carrier in its transverse guide, 16, on the reciprocable head, 14. To accomplish this I have connected to the said knife carrier at one side a connecting rod, 21, jointed at its outer end to a depending arm of a bell crank lever, 22, fulcrumed 110 at 23, in a bracket, 24, on one of the frame side members. This bell crank lever has two horizontal arms, marked respectively 25, and 26, see Fig. 7. The arm, 26, is forked at its end to embrace the flanged sleeve, 27, loose 115 on the slide rod, 28, mounted in suitable bearings, 29, on the frame. At its opposite ends said collar, 27, is supported by springs, 30, seated at their outer ends respectively against a collar, 31, and an arm, 32^X, both 120 fast on the rod, 28, so that reciprocation of said rod will act through the said springs, 30, to rock said arm, 26, the springs permitting a uniform reciprocation of the rod, even though the arm, 26, be permitted to have a 125 limited rocking movement only.

The rod, 28, is reciprocated by means of a connecting rod, 31, see Figs. 1, 2 and 7, from

a crank pin, 32, on a shaft, 33, journaled in bearings in the side frame members. This shaft, 33, has fast upon it a gear wheel, 34, driven by a pinion, 35, on the main shaft, 2, 5 the gear being such as to rotate the said shaft, 33, at one-half the speed of the main shaft.

From the foregoing it will appear that reciprocation of the slide rod, 28, through its springs, 30, will rock said arm, 26, and the 10 bell crank of which it is a part, and through the said bell crank and the connecting rod, 21, Fig. 1, will impart transverse reciprocation to the knife carrier and its knife in the reciprocating slide, 14, so that the said knife 15 has a combined up and down or chopping movement and also an endwise sliding movement to produce a cut that is longer than the width of the knife itself.

I will now describe the means for supporting and feeding the sole to present the latter to the reciprocating knife.

Referring particularly to Fig. 4, the bed of the frame is provided with an anvil, 36, presenting an outer curved face over which the 25 sole may be drawn, as indicated in dotted lines. Immediately behind the anvil is the, feed roller, 37, and above it the presser roller, 38. The feed roller, which preferably is of metal with a corrugated or roughened 30 surface, but which may have a rubber or other yielding surface, if desired, is fast upon a shaft, 39, journaled in the frame and provided at its righthand end (Figs. 1 and 2) with a suitable, preferably roller, clutch, 40, 35 having an actuating arm, 41, controlled by a spring, 42, attached to the frame.

Referring to Fig. 7, the arm 32^x on the slide rod, 28, previously referred to, carries in its outer end a clutch actuator, 43, which 40 slides in the bearing, 29, referred to, and at its lower end, see Fig. 2, is provided with an actuator block, 44, adapted at each reciprocation of said slide rod to engage the clutch actuator, 41, and move it to the left, Fig. 2, 45 to impart a step movement to the feed roll, 37. Upon each upward movement of said slide rod the spring 42 retracts the clutch actuator preparatory to a new engagement for another feeding movement at the next 50 succeeding reciprocation of said rod.

The reciprocation of the slide rod being of uniform length, while the feed for the best results should be capable of variation, I have provided upon the side of the bed, see Fig. 2, 55 an adjustable stop, 45, which serves to limit the return or retractile movement of the clutch actuator under the influence of its spring, and thereby determine the extent to which the clutch actuating rod, 43, may 60 move it in its downward pushing movement. Since the clutch actuator always pushes the clutch arm, 41, to a given position, it is evident that any variation in the return or retractile movement will produce a correspond-

ing variation in the effective feed given to 65 the feed roller.

At the opposite side of the machine the feed roll shaft is provided with a back stop clutch, 46, similar in construction to the feed clutch, 40, but reversely acting, said clutch, 70 46, serving to hold the feed roll always in the position to which it has been moved so as to prevent the roll returning with the clutch return.

Returning again to Fig. 4, the presser 75 roller, 38, is loosely mounted in a pair of arms, 47, loosely mounted upon the shaft, 48, journaled in the side frame members. These arms, 47, are provided respectively with rearwardly extended tail portions, 49, 80 provided with adjusting screws, 50, which are acted upon by presser springs, 51, seated in the frame, and which tend to throw the presser roller, 38, normally downward into contact with a sole resting upon the feed roll. 85 This downward spring actuated movement of the presser roller is normally restrained and controlled by contact with two pins, 52, carried in a pair of arms, 53, that are fast on said shaft, 48, and carry at their outer ends 90 a flexing or bending roller, 54. The said shaft, 48, is provided with a treadle arm, 55, connected by a rod, 56, with a suitable treadle (not shown), and is provided with a return spring, 57, acting in opposition to the 95 treadle, said spring, 57, being of sufficient strength to overcome the presser springs, 51, and normally compress the latter to hold both the flexing roller, 54, and the presser roller, 38, normally in their elevated positions.

In the rear of and between the presser and feed rollers stands a feeding stop, 57^x, on a rod, 58, adjustably mounted in an arm, 59, on a shaft, 60, mounted in the frame. Said 105 shaft is provided with a second horizontally extended arm, 61, that overlies an ear, 62, on one of the flexer arms, 53.

The sole to be slashed is inserted toe end 110 first over the anvil beneath the knife and between the feed and presser rollers with its end abutting against the stop, 57^x. The operator now depresses the treadle and brings the presser and flexing rollers down upon the sole. The presser roller 38 first 115 contacts with the sole and there rests under the action of its springs, 51, so as first to grip the sole and hold its leading end accurately in position. Further movement of the treadle brings the flexing roller, 54, down upon 120 the sole to bend or flex the latter down over and upon the curved face of the anvil, 36, so that that portion of the sole which is to receive the cut of the knife is always bent into convex form, with its top face under tension 125 and calculated to receive a slash with the least effort and with the cleanest cut by the knife. As the flexer roller is advanced its

ear, 62, rises under the arm, 61, of the abutting stop, 57^x, and lifts said stop into a position above the level of the sole so as not to interfere with the feed of the latter between its rollers. If, now, the driving clutch be thrown into operation, the rotation of the driving shaft will cause the slashing knife to reciprocate rapidly to chop a series of slashes in the insole as the latter is fed step by step between the feed and the presser roller, the machine being timed so that each slash cut takes place during a period of rest between successive feeds of the sole and said knife, as stated, is given a transverse or endwise movement between successive downward cutting movements.

As stated in the preamble, the areas to be slashed are rarely alike either in shape or extent, but however irregular these areas may be either as to shape or extent, both the shape and extent as a rule are substantially accurately represented by the peripheral or marginal edge of the sole, and therefore in the machine here disclosed I work from the periphery of the sole to determine both the shape and area to be slashed. To accomplish this, see Figs. 1 and 5, I have pivoted to the front edge of the bed at 63, two feeler arms, 64, that rise in a direction substantially parallel with the inclined front of the machine, and intermediate their lengths are provided with inwardly and upwardly extended contact ears, 65, adapted to press against and to follow the outline of the peripheral edges of a sole fed between them. Said feelers are drawn normally toward each other by a connecting spring, 66, Fig. 5. Obviously, as a sole is fed between these feelers they will be gradually spread and afterwards contracted according to and following the shape of the sole and the extent to which they are so separated and contracted will represent the area of the sole, a portion of which is to be slashed. To communicate this tell-tale or measuring action to the cutter for limiting the transverse reciprocations of the latter, I have connected the upper ends of the said feelers, 64, by links, 67, with two oppositely tapering wedge-shaped slides, 68, and 69, mounted to slide in suitable bearings, 70, on the frame. Obviously, as these feelers are spread by the increasing width of the sole, the opposite movements of the wedge slides 68, 69, will cause the inclined or wedged faces to be effectively separated, and conversely as these feelers approach to indicate a narrowing sole, the opposite return movements of said wedge slides will effectively contract the space between their beveled or inclined faces. It is likewise true that if one sole edge were straight and the other one were curved, or if one presented less curvature than the other, in each case the wedge slides for the respective sole edges would by their positions cor-

rectly indicate the shape of sole being fed 65 through the machine.

Playing transversely between the inclined faces of these slides is the downturned end of a stop rod, 71, which, see Fig. 7, is extended substantially parallel with the slide rod, 28, 70 and is mounted at one of its ends in a bearing, 72, on the frame, and at its opposite end in a cap, 73, covering the wedge slides, 69. Loosely mounted on this stop rod is a flanged sleeve, 74, centered between springs, 75, seated against collars, 76, fast on said stop rod. The spring centered collar, 74, is embraced by the forked end of the second arm, 24, of the bell crank heretofore referred to. It will now be clear that the oscillations of the bell 80 crank which reciprocate the knife transversely are limited by the play of the stop rod, 71, between the wedge slots 68, 69, and that the separation of said slides determines the length of transverse reciprocation of the 85 knife, which may vary from time to time according to the shape of the sole. Consequently, the excess movements of the slide rod, 28, beyond the oscillatory movement permitted to the bell crank, are taken up in 90 compressing one or the other of the springs, 30, the shorter and stiffer springs, 75, between the stop rod and its bell crank arm, 24, being merely cushioning stops to relieve any 95 shocks which might otherwise be produced by abruptly stopping the rapidly reciprocating knife.

The wedges 68, 69 are shown as adjustably connected by screws 76, 77, with their respective slides to permit said wedges to be adjusted on their slides to provide for any desired unslashed margin on the sole within the periphery of the latter. Thus, it is possible to limit the transverse reciprocations of the knife so that they will slash an area reaching 105 only to the channel or lip of an insole or to a given marginal distance within the periphery of a "McKay" or other insole, such margin always following the shape of the sole and leaving the slashed area always correspond- 110 ing in outline to that of the sole.

While I prefer that the feelers operate on the peripheral edges of the soles, yet they could of course be made to operate upon an upturned channel or any other guiding surface provided upon the sole.

To render the machine automatic in its action so that it may be gaged to permit an operator to insert a sole in one machine and while it is being slashed remove a slashed sole from another machine and reinsert a new sole in the latter, I have provided means for stopping the machine at the end of a given number of effective movements, or, expressed differently, after it has produced a 125 given number of slashes. This mechanism is best illustrated in Fig. 3.

The driving clutch heretofore referred to

is provided, as stated, with a controlling ear, 10, which underlies a hooked block, 78, mounted to slide on a stud, 79, projecting from an arm, 80, fast on a short shaft, 81, 5 journaled in one of the frame side members. On the inner end of this short shaft 81, Fig. 8, is made fast an arm 82, acted upon by a spring, 83, seated in the frame and which tends to throw said hooked block, 78, normally into a position overlying the said clutch ear, 10, to hold the latter. This spring-actuated movement, see Fig. 8, is limited by an adjustable stop screw, 84, on the ear of said arm, 82.

15 The hooked block, 78, is cushioned above by a spring, 85, seated against one or more nuts, 86, threaded upon the end of said stud, 79.

Assuming the driving shaft to be in rotation and the machine in operation, it is clear 20 that if the hooked block, 78, be swung into position in the path of movement of the rapidly revolving clutch ear, 10, that the latter will engage said hooked block and be suddenly arrested, the stop being cushioned by 25 the spring, 85, and this arresting of the said ear and its attached roller cage causes immediate disengagement of the clutch, followed by arresting of the shaft, 2, by reason of a stop pin, 85^x, between the clutch members, 30 although in actual practice the spring, 9, will serve to arrest the shaft before the stop becomes effective. To move this hooked block into and out of engaging position I have mounted loosely about its shaft, 81, a 35 lever, 86^x, having one of its ends forked and provided with adjustable stop screws, 87; that embrace the arm, 80, upon which the hooked block is mounted. These screws furnish means for adjusting the inward position of said hooked block as may be desired. The opposite end of said lever, 86^x, is provided with a stud, 88, which plays in a slot, 89, in the upper end of a toggle connection, 90, between said lever 86^x, and an arm, 91^x, 40 fast on one of the flexer arms, 53, at the left-hand side of the machine. By means of this connection whenever the flexer arm is moved to flex the sole and start the machine, the toggle connection, 90, acts to lift the arm, 86^x, and throw the hooked block, 78, away 45 from the shaft, 2, to free the clutch and set the machine in motion. Conversely, if the treadle be released, or if the parts be otherwise oppositely moved, said hooked block 50 will be thrown into position to disengage the clutch and stop the machine. To accomplish this automatically is one of the purposes of making the connection, 90, as a toggle, its two parts being jointed at 91 and 55 drawn together by a spring, 92. The collapse of the toggle connection under the spring action is prevented by a stop block, 93, at the opposite side of the connection and attached to the frame, the joint pin, 91, being

extended through so that its protruding end 65 may bear against the edge of said block, 93.

When the arm, 91^x, is raised to arrest the toggle connection and start the machine, this pin, 91, rides up the side of said block and springs over the top thereof into a seat, 94, 70 provided therefor, and which supports said pin, the connection, and the parts operated thereby in the position into which they are moved to start the machine. And to stop the machine, this pin must be disengaged 75 from its seat to permit the connection to drop. For this purpose I have provided upon the side of the machine a toothed slide bar, 95, mounted at its under side in the bearing, 96, and at its upper side confined by 80 a roller, 97, and also at its upper end at the same side by the yielding support, 98. Near its upper end this sliding bar is provided at its under side with a series of teeth constituting a rack, 99, adapted to be engaged by a 85 crank pin, or single toothed gear, 100, fast on the end of the shaft, 33, previously referred to. Near its lower end said bearing is provided at its under side with a series of ratchet teeth, 101, and at its lower end with 90 a disengaging ear, 102. The upper member of the toggle connection, 90, is provided at its inner side and between it and the side frame with a pawl, 103, acted upon by a spring, 104, and when the connection is raised to 95 start the machine this pawl is brought into engagement with the ratchet toothed under edge of the slide bar, 95. When, now, the machine is started, rotation of said shaft, 33, acts through its single toothed gear, 100, to 100 move said bar step-by-step upward, it being held in each stepped position by one of its ratchet teeth resting upon the pawl, 103, the machine continuing its operation until in this gradual step-by-step upward movement the 105 disengaging ear, 102, strikes the toggle joint of the connection, 90, when the next succeeding step movement of said bar causes said ear to break the toggle, disengage it sufficiently to unseat it from the block, 93, and 110 permit the parts to return to their normal positions with the notched block, 78, in the path of movement of the clutch ear to stop the machine.

The dropping of the toggle connection releases the notched bar and the latter slides downward to its starting position, where it is arrested by a plug stop, 105. A series of holes is provided for this plug stop, into any of which it may be placed for varying 115 gravity movement of the notched slide and, obviously, the position in which it is arrested in this return movement determines the number of teeth required to raise it before it will unseat the toggle connection, and consequently the number of slashes to be made 120 by the machine before it is automatically stopped.

My machine, therefore, herein disclosed and illustrating one form of my invention, provides not only means for predeterminedly varying the shape and width of the 5 slashed area, but also the length of such area, and so far as known to me this is the first machine having these capacities or any of them.

I have previously stated that at its upper 10 end the notched rack slide, 95, is yieldingly supported by the support, 98; this support is shown in detail in Fig. 9, its spring being marked 106. If the slide, 95, be obstructed and prevented from gravitating freely to its 15 lowermost position, this yielding support will permit it to give way before the rotating single toothed gear, 100, and prevent damage to the parts.

Should the operative maintain the treadle 20 depressed, thereby preventing the toggle connection, 90, from dropping to stop the machine, the continued movement of the toothed slide, 95, will cause its ear, 102, to break the toggle sufficiently to shorten the 25 connection and thereby stop the machine, even though the treadle remain depressed. This collapse of the toggle is facilitated the moment the dead center line is passed by the spring, 83, Fig. 8, acting on and controlling 30 the arm, 80.

To prevent rebound of the clutch and driving shaft when the latter are stopped, Fig. 3, I have provided the clutch housing 8, with a segmental series of ratchet teeth, 107, adapted 35 to be engaged by a spring-supported pawl, 108, on the arm, 80, when said arm is thrown into clutch-engaging position.

While I have found it convenient to feed the sole straight through and constitute the 40 knife the reciprocable member, obviously the reverse would be the mechanical equivalent thereof, making the sole the reciprocable member. In other respects, also, it must be understood that the embodiment of my invention here shown and described is simply 45 illustrative thereof and, I believe, the best, though not the only, embodiment thereof.

Claim

1. A shoe sole slashing machine comprising, in combination, reciprocating slashing means; and actuating means therefor, to produce progressively a slashed area comprising slashes of varying lengths.

2. A slashing machine comprising the combination of slashing means for producing a slashed area of separate slashes, and slash elongating means.

3. In a shoe sole slashing machine, the combination of slashing means for producing a slashed area comprising a plurality of separate slashes and means relatively to move the slashing means and work to elongate a slash.

4. In a slashing machine, the combination

with a slashing means arranged to form a 65 slashed area comprising a plurality of separate slashes, of means to cause the same to act upon the work in a plurality of positions for making a single slash.

5. A slashing machine comprising in combination, slashing means for producing a plurality of separate slashes in the surface of a shoe sole, and means to cause the slashing means to act progressively along the line of a proposed slash to determine the length of the 75 latter.

6. A slashing machine, comprising in combination, a slashing blade, a work support, and actuating means for causing the blade to form separate slashes in the work, including 80 means relatively to move the blade and work to elongate the same.

7. A shoe sole slashing machine, comprising in combination, slashing means constructed and arranged to form a slashed area 85 of separate slashes, and means for causing the slashing means to act upon the work in a plurality of positions transversely of the work.

8. A slashing machine comprising, in combination, slashing means; and means for 90 causing the slashing means to act alternatively at different distances from an edge of the work.

9. A slashing machine comprising, in combination, slashing means; and work governed 95 means to vary the slashed area of the work.

10. A slashing machine comprising, in combination, slashing means; and automatic 100 slash-positioning means to vary the locations of slashes to produce a slashed area on the work for the time being operated upon.

11. A slashing machine, comprising, in combination, slashing means; and means co-operating with the work to determine the 105 length of a slash by reference to a dimension of the work.

12. A slashing machine comprising, in combination, slashing means; actuating means therefor, including means to produce a slashed 110 area of varying dimensions; and means to determine dimensions of the slashed area controlled by the dimensions of the work.

13. A slashing machine, comprising in combination slashing means; and automatic 115 work-controlled slash-positioning means to cause slashes to follow a predetermined contour relative to the work being operated upon in the production of a slashed area comprising a plurality of separate slashes.

14. A slashing machine comprising, in combination, slashing means; means for causing the same to produce progressively a slashed area comprising slashes of varying lengths; and automatic means to determine 120 the number of said slashes.

15. A slashing machine comprising, in combination, slashing means; automatic work-

- governed means to vary the slashed area produced by the slashing means; and adjustable means to determine the number of slashes in said area.
- 5 16. A slashing machine comprising, in combination, reciprocating slashing means acting progressively to make separate slashes of varying lengths to form a slashed surface; and flexing means to flex the work to be operated upon by the reciprocating slashing means.
- 10 17. A slashing machine comprising, in combination, slashing means; actuating means therefor; means to vary the lengths of slashes; and means to change the spacing between slashes.
- 15 18. A slashing machine comprising, in combination, slashing means; means for causing the slashing means to act upon the work in a plurality of positions transversely of the work; and variable means for determining the spacing between successive slashes.
- 20 19. A slashing machine comprising, in combination, slashing means; actuating means therefor; means to determine the position of an initial slash; means to determine the intervals of space between slashes; means to determine the number of slashes; means to determine the length of each slash; and means to vary said determining means respectively, whereby the character and dimensions of a slashed area may be accurately determined.
- 25 20. A slashing machine comprising, in combination, slashing means; actuating means therefor; means to act on an end of the work to determine the location of a slash lengthwise of the work; and means to act upon a side portion of the work to determine the location of a slash transversely of the work.
- 30 21. A slashing machine comprising, in combination, slashing means; and slash-positioning means, including alternatively-effective surfaces to govern the slashing according to the work presented.
- 35 22. A slashing machine comprising, in combination, slashing means; and alternatively-effective work-governed slash-positioning surfaces to locate slashes in accordance with the area of work intended to be operated upon.
- 40 23. A slashing machine comprising, in combination, a work-support; a cutter arranged to act upon the surface of a shoe sole; means relatively to reciprocate the cutter in a plurality of directions to produce a slashed area, said slashed area comprising a plurality of separate slashes; and means to cause predetermined variation in limits of said reciprocations in one direction.
- 45 24. A slashing machine comprising, in combination, a work support, a cutter ar-
- ranged to act upon the surface of the shoe sole; means relatively to reciprocate the same in a plurality of directions to produce a slashed area of separate slashes; and means variable according to the particular sole to be slashed to vary the said reciprocations in one direction.
- 50 25. A slashing machine comprising in combination a work support, a cutter constructed and arranged to form a slashed area comprising a plurality of separate slashes, means relatively to reciprocate the same in a plurality of directions to produce slashes in the surface of the shoe sole in different locations, and means governed by the sole to be slashed to vary said reciprocations in one direction.
- 55 26. A slashing machine comprising in combination a work support, a cutter constructed and arranged to produce a slashed area comprising separate slashes, means relatively to reciprocate the cutter and work support in a plurality of directions, and means governed by the sole to be slashed to vary said reciprocations in one direction, thereby to adapt the slashes to the governing sole.
- 60 27. A slashing machine comprising, in combination, a work support; a cutter; means relatively to move the same for slashing a sole; feed rollers normally separated; a stop beyond and opposite the space between said rollers; and means to bring said rollers into feeding contact with the sole and also to remove said stop from the path of feeding movement.
- 65 28. A slashing machine comprising, in combination, a work support; a cutter; means relatively to move the same for slashing a sole; normally separated feeding devices; a flexer; and means to cause effective engagement of said feeding devices with the sole and for following the same with effective engagement of said flexer also with said sole.
- 70 29. A slashing machine comprising, in combination, a work support; a cutter; a cutter carrier; a slide on which said carrier is mounted; means to reciprocate said slide; and means also to reciprocate said carrier on and transversely of said slide, the transverse reciprocations occurring uniformly one for a given plurality of slide reciprocations.
- 75 30. A slashing machine comprising, in combination, a work support; a cutter; a slide for reciprocating said cutter in one direction; means to reciprocate said cutter on and transversely of said slide; said means being yieldingly connected with said cutter whereby the transverse reciprocations may be varied relative to said means; and means to vary said transverse reciprocations according to the sole or piece of work operated upon.
- 80 31. A slashing machine comprising, in combination, a work support; a cutter; means to impart endwise reciprocation to the

latter; means to impart variable transverse reciprocations to said cutter; work feeding means; and means governed by the work fed into the machine to vary the said transverse reciprocations.

32. A slashing machine comprising, in combination, a work support; a reciprocable cutter; feeding means; means acted upon by the work fed into the machine and responsive to changing widths of said work; and limiting devices controlled by said last mentioned means to determine the limits of reciprocation of said cutter.

33. A slashing machine comprising, in combination, a work support; a reciprocable cutter; feeding means; measuring means acting upon opposite sides of the work fed into the machine and responsive to variations in width of said work; means to press the same yieldingly towards each other; and reciprocation limiting devices controlled by said measuring means.

34. A slashing machine comprising, in combination, a work support; a knife; means for causing the knife to act upon the work; knife adjusting means to change the operative position of the knife in relation to the work; a pair of measuring arms to coöperate with the work; and governing means for the knife adjusting means including opposed oblique surfaces movable upon movement of said measuring arms respectively to present different degrees of separation whereby to determine the extent of effective operation of said knife adjusting means.

35. A slashing machine comprising, in combination, a knife; knife adjusting means to vary the operative position of the knife in relation to the work; measuring means to coöperate with opposite sides of the work; and limiting stops for the knife adjusting means, governed by the measuring means.

36. A slashing machine comprising, in combination, a work support; a reciprocable knife; means, having a fixed range of movement, yieldingly connected with and to reciprocate said knife; feeding means; measuring devices operable upon the edges of the work; and variable stop means controlled by said measuring means to limit the reciprocations of said knife relative to its actuating means.

37. A slashing machine comprising, in combination, a work support; a reciprocable knife; means to vary the limits of reciprocation by reference to the work fed through the machine; and cushioning means for said reciprocation varying means.

38. A slashing machine comprising, in combination, a work support; a cutter; means relatively to reciprocate the same; means governed by the work fed to the machine to vary the limits of reciprocation of said cutter; and feeding means to feed the

work intermittently at the end of each reciprocating movement.

39. A slashing machine comprising the combination of progressively acting slashing means, and progressively effective work governed means for confining the slashing within a desired area.

40. A slashing machine comprising the combination of slashing means for making a plurality of slashes in succession, and automatic work governed means operative preparatory to the making of each slash to determine the location of the prospective slash upon the work.

41. A machine of the class described comprising, in combination, the work support 36; the knife 18; means to reciprocate said knife; and knife-shifting mechanism including a shaft 33, a slide rod 28 reciprocated thereby, a bell crank 22, springs 30 between the rod 28 and bell crank 22, and a rod 21 to communicate movement of the bell crank to the knife, substantially as described.

42. A machine of the class described comprising, in combination, the work support 36; knife 18; means to reciprocate the knife; a connecting rod 21 for shifting the knife laterally; means to operate said connecting rod; a feed roller 39 and depresser 38 to present successive portions of the work to the knife; and a stop 57^x to determine initial adjustment of the work.

43. A machine of the class described comprising, in combination, a work support 36; a knife 18; its moving slide 14; a connecting rod 21 to move the knife on said slide; actuating means for said slide and connecting rod; and a flexer 54 to flex the work preparatory to the action of the knife.

44. A machine of the class described comprising, in combination, a work support 36; a knife 18; its moving slide 14; a connecting rod 21 to move the knife on said slide; actuating means for said slide and connecting rod; and a measuring device 64 to coöperate with the work for controlling a movement of said connecting rod.

45. A machine of the class described comprising, in combination, a work support 36; a knife 18; a rod 21 to adjust the knife; actuating means for the rod, including a stop device 71 to vary the effectiveness of the actuating means; and adjustable wedge slides 68, 69 to control the action of said stop device 71.

46. A machine of the class described comprising, in combination, a work support; slashing means; starting and stopping means for said machine; a toothed slide 95 movable synchronously with the slashing means; and an ear 102 moved by said slide to disorganize the starting and stopping mechanism and stop the slashing operation after a predetermined number of slashes.

47. A machine of the class described comprising, in combination, a work support; slashing means; starting and stopping means for said machine including a jointed connection 90 and a rest 93 to govern the joint; a toothed slide 95 movable synchronously with the slashing means; an ear 102 operated by the slide 95 to stop the machine; a yielding sliding support for the slide 95; and a gear 10 100 for operating the slide 95.

48. A slashing machine comprising in combination slashing means for producing a

slashed area of separate slashes, and actuating means for causing successive actions of the slashing means to produce slashes of .15 different lengths.

In testimony whereof, I have signed my name to this specification, in the presence of two subscribing witnesses.

WILLIAM C. STEWART.
